[57] CLAIM

The ornamental design for a hot plate, as shown.

DESCRIPTION

FIG. 1 is a front elevational view of a hot plate showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is an enlarged cross-sectional view taken along line 7—7 of FIG. 1 with the internal mechanism omitted;

FIG. 8 is a perspective view thereof;

FIG. 9 is a front elevational view of a second embodiment of a hot plate showing our new design;

FIG. 10 is a rear elevational view thereof;

FIG. 11 is a right side elevational view thereof;

FIG. 12 is a top plan view thereof;

FIG. 13 is a bottom plan view thereof;

FIG. 14 is an enlarged cross-sectional view taken along line 14—14 of FIG. 9 with the internal mechanisms omitted;

FIG. 15 is a perspective view thereof;

FIG. 16 is a front elevational view of a third embodiment of a hot plate showing our new design;

FIG. 17 is a rear elevational view thereof;

FIG. 18 is a left side elevational view thereof;

FIG. 19 is a right side elevational view thereof;

FIG. 20 is a top plan view thereof;

FIG. 21 is a bottom plan view thereof;

FIG. 22 is an enlarged cross-sectional view taken along line 22—22 of FIG. 16 with the internal mechanisms omitted; and

FIG. 23 is a perspective view thereof.
